UNITED STATES PATENT OFFICE.

FERDINAND THOMAS, OF NEW YORK, N. Y.

TILE STRUCTURE.

1,106,168.

Specification of Letters Patent.

Patented Aug. 4, 1914.

Application filed February 19, 1912, Serial No. 678,461. Renewed January 22, 1914. Serial No. 813,770.

To all whom it may concern:

Be it known that I, FERDINAND THOMAS, a citizen of the United States, and a resident of the city of New York, borough of the Bronx, in the county and State of New York, have invented a new and Improved Tile Structure, of which the following is a full, clear, and exact description.

Among the principal objects which the present invention has in view are: to provide efficient, economical and simple means for retaining ceramic and other tile in service position; to avoid the use of cement or other plastic material; and to form a backing or register for tile of the character mentioned to permit the removal of the tile from service position.

Reference is to be had to the accompanying drawings forming a part of this specification, in which similar characters of reference indicate corresponding parts in all the views.

Figure 1 is a view in perspective of the side wall of a standing structure showing the same as having applied thereto a retaining backing constructed and arranged in accordance with the present invention, and tile as applied thereto; Fig. 2 is a detail view on an enlarged scale showing in cross section a furring strip, a retainer backing, and tile applied thereto, all constructed and arranged in accordance with the present invention; Fig. 3 is a cross section showing a tile and retainer backing therefor for the finishing course of a tile-laid surface; Fig. 4 is a perspective view of a tile construction and arranged in accordance with the present invention; Fig. 5 is a detail view of fragments of strips of the herein-described backing, the same being illustrated in separated relation; and Fig. 6 is a view of the back of a tile used to form the finishing course of a tile-laid surface.

As seen in the accompanying drawings, tiles 10, when constructed in conformity with the present invention, have provided a centrally disposed channel 11 opening to the back of the tile. The sides of the said channel over-hang, the preferred shape being, as shown in the drawings, what is known as a dove-tailed channel. The outer edges of the tile parallel with the channel 11 are formed to provide the over-hanging edges 12, which, together with the projected edges 13, 13, form a V-shaped groove at the edge of each tile. The V-shaped groove

thus produced is preferably equal to each of the channels 11. To support the tiles thus constructed, there is provided a sheathing plate 14. The plate 14 is corrugated to form at suitable intervals, ribs 15. The shape of the ribs 15 in cross section coincides with the shape of the channel 11, fitting the same snugly when the tile is mounted on the said sheathing plate.

The sheathing plates are constructed from suitable sheet metal, and are fastened to the standing structure and to the furring strips 16 thereof by means of nails 17, or other suitable fastening devices. The plates 14 may be disposed on the furring strips in any desired manner, that is to say, the ribs 15 may be extended horizontally, vertically or obliquely. In whatever manner the ribs 15 do extend, the tiles 10 are mounted thereon by slipping the tiles thereover, with the ribs disposed within the channels 11 and the V-shaped grooves formed by the over-hangs 12 and edges 13. This arrangement is seen best in Figs. 1 and 2 of drawings.

The tiles 10 are successively mounted on the ribs 15. When the side wall, floor or ceiling which is being constructed approaches the finishing course, it will be understood that the main body of the sheathing plates 14 must be arrested or the ribs 15 thereof must terminate so as to provide an entrance space for the tile 10 to thread within the channels 11 thereof, the ribs 15. When the last but one course of the tiles 10 has been laid, the finishing strip 18 is nailed or otherwise secured to the furring strip 16, with the rib 15 formed thereon extending perpendicularly to the ribs 15 on the plates 14. The finishing tiles 19, as seen in Fig. 1 of the drawings, are now introduced into the plates by being threaded upon the rib 15 of the strip 18. The first of the tiles 19 is moved along the strip 18 until forming a joint with the supporting edge of the tile-laid structure. All succeeding tiles are entered upon the strip 18 until the last. It will be understood that the structure compels the formation of a space at one end of the strip 18 where the rib 15 is reduced so that the tiles 19 may each be adjusted in line with the rib 15 to be moved thereover to provide the finishing course of the tiles. It now becomes necessary to provide a key block and means for securing the same in position. This is shown best in Figs. 3 and

6, where the key tile 20 is shown as having a central channel 22, the channel being provided with laterally disposed rectangular grooves 21. The opening of the channel 22, 5 as seen best in Fig. 3, is sufficiently wide to pass the head of the rib 23 which is formed on the plate 24. The plate 24 is a special plate added to the backing for the tile in the position provided for the key tile. The 10 ground of the ribs 23 is so reduced as to pass freely between the edges of the channels 11 of the tiles 19, and in this manner avoid interfering with the threading of the tiles 19 upon the rib 15 of the strip 18. The 15 arrangement of the plate 24 is illustrated in Fig. 1, where it will be noted the finishing course of tiles 19 has been moved from the left of the said figure to the right of the 20 said figure, to form the course the first of the tiles so introduced being indicated by the letter *a* and as disposed in the corner of the tile structure. The key tiles 20 are each provided with latch springs 25. Each of the springs is, as seen in Figs. 3 and 6, disposed in one of the grooves 21. Each of the springs is provided with a series of latch heads 26, 26, shaped, as seen in Fig. 3, to rest upon the inclined sides of the rib 23 to grip the same when the said tile is forced 30 directly inward against the surface of the plate 24 and upon the rib 23. When the tile 25 is thus forced upon the rib 23 the springs yield to permit the avoidance by the heads 26 of the rib 23. It will be seen that 35 starting from any given point and ending against a side wall, as the corner of a room, either the corner of the floor with the side wall, or of two side walls, the finishing course of the tile structure is thus laid and

finally secured by a tile. It will also be 40 noted that when the tiles 10, 19, 20 have been thus mounted upon the backing 14, 18 and 24, the structure is rigidly, permanently and neatly held in position.

As seen in Fig. 5 of drawings, the ribs 45 15, 15 are projected at one end of the plates 14 to form the overhanging sections 27. To accommodate these overhanging sections, the ribs are removed from the matching edge of the adjacent plate 14 to leave the 50 tongue sections 28. The overhanging sections 27 of the ribs 15 on the one plate rest above the tongue sections 28 and register with the ribs 15 on the adjacent plate 14. In this manner the passage of the tiles 10 55 from one to another of the plates 14 is effected without jam or jar.

Having thus described my invention, I claim as new and desire to secure by Letters Patent:

In a tile structure having a backing provided with ribs, the edges whereof overhang, and tiles having undercut grooves to register with said ribs to slide longitudinally thereon; a key tile having a groove at 65 the back, said groove being as wide as said ribs, and the sides of said groove being recessed; and a plurality of resilient members mounted in said recesses to engage one of said ribs after the tile has been forced thereover.

In testimony whereof I have signed my name to this specification in the presence of two subscribing witnesses.

FERDINAND THOMAS.
